UNITED STATES PATENT OFFICE.

DONALD S. BARROWS, OF ROCHESTER, NEW YORK.

DESIGN FOR A DRAFT-YOKE.

56,491.

Specification for Design.

Patented Nov. 2, 1920.

Application filed July 5, 1918. Serial No. 243,492. Term of patent 14 years.

To all whom it may concern:

Be it known that I, DONALD S. BARROWS, a citizen of the United States, residing at Rochester, in the county of Monroe, State of New York, have invented a new, original, and ornamental Design for a Draft-Yoke, of which the following is a specification, reference being had to the accompanying drawing, forming part thereof.

Figure 1 is a perspective view of a draft yoke showing my new design.

Fig. 2 is a longitudinal central section showing one arm of the yoke in side elevation.

Fig. 3 is a top plan view of one end of a yoke arm.

Fig. 4 is an end elevation of a yoke arm. Figs. 5, 6 and 7 are, respectively, transverse vertical sections taken on the correspondingly numbered lines of Fig. 2 looking in the direction indicated by the arrows, and

Fig. 8 is a horizontal transverse section taken on line 8—8 of Fig. 2.

I claim:

The ornamental design for a draft yoke, as shown.

In testimony whereof I hereunto affix my signature.

DONALD S. BARROWS.
